UNITED STATES PATENT OFFICE.

CHARLES BROOKS, OF NEW YORK, N. Y.

DESIGN FOR A PATTERN FOR PIPE-COVERINGS.

SPECIFICATION forming part of Design No. 28,573, dated May 10, 1898.

Application filed August 21, 1897. Serial No. 649,084. Term of patent 14 years.

To all whom it may concern:

Be it known that I, CHARLES BROOKS, a citizen of the United States, residing at New York city, in the borough of Manhattan and the State of New York, have invented and produced a new and original Design for a Pattern for Pipe-Coverings, of which the following is a specification, reference being had to the accompanying drawings, forming part thereof, and which represent my new design.

Figure 1 is a surface view of my covering. Fig. 2 is a vertical cross-section along the line 2 2 of Fig. 1. Fig. 3 is a vertical cross-section along the line 3 3 of Fig. 1. Fig. 4 is a vertical cross-section along the line 4 4 of Fig. 1.

Similar letters of reference indicate corresponding parts throughout the drawings.

The leading or material feature of my design consists in a series of ribs and grooves disposed and arranged as shown.

Referring to the letters in the drawings, A is a depression. B is an upraisure; C, an upraisure; D, a depression; E, a smooth horizontal part, while F is a depression, G the upraisure behind it, and H a smooth horizontal part like E.

Having described my invention, what I claim as new, and desire to secure by Letters Patent, is—

The design for a pattern of pipe-covering, substantially as shown and described.

Signed at New York, in the county of New York and State of New York, this 10th day of August, A. D. 1897.

C. BROOKS.
